Primary Examiner — Katherine A Holbrow(74) *Attorney, Agent, or Firm* — Dinsmore & Shohl LLP**CLAIM**

The ornamental design for a display screen with a widget, as shown and described.

DESCRIPTION

FIG. 1 is a front view of a display screen with a widget; and, FIG. 2 is a detail of FIG. 1, shown enlarged for clarity of illustration.

The outermost broken line rectangle shows the display screen, and forms no part of the claimed design. All other broken lines show portions of the graphical user interface and form no part of the claimed design.
